UNITED STATES PATENT OFFICE.

WILLIAM J. BLEY, OF SILVER KING, ARIZONA TERRITORY, ASSIGNOR TO HIMSELF AND ROBERT BOWEN, OF SAME PLACE.

MACHINE FOR FRAMING TIMBER.

SPECIFICATION forming part of Letters Patent No. 309,021, dated December 9, 1884.

Application filed August 15, 1884. (No model.)

To all whom it may concern:

Be it known that I, WILLIAM J. BLEY, of Silver King, in the county of Pinal and Territory of Arizona, have invented a new and 5 Improved Machine for Framing Timbers, of which the following is a full, clear, and exact description.

My invention relates to sawing-machines for cutting tenons on the ends of timbers—such as the “square set” for supporting the earth and rock around shaft, drift, and tunnel cuttings, and for use in framing timbers for other uses within the capacity of the machine.

The invention consists in a timber-framing 15 machine constructed with two saws mounted to cut at right angles to each other in a fixed saw-frame, and with a traversing timber-carriage provided with rotatable timber-clamps, by which the timber may be turned axially to 20 present all of its faces to the saws, and that section of the carriage which carries the timber-clamps being mounted to rotate horizontally to present both ends of the timber to the saws, and the timber-clamp frame being 25 adjustable toward and away from the saws, to govern the lengths of the framed timbers. The invention includes, also, special constructions of the timber clamps and carriage, and of the mechanism for setting the timber with relation 30 to the saws, all as hereinafter fully described and claimed.

Reference is to be had to the accompanying drawings, forming part of this specification, in which similar letters of reference indicate 35 corresponding parts in all the figures.

Figure 1 is an end elevation of the machine with the timber-carriage drawn forward away from the saws. Fig. 2 is a front elevation, partly in section and with parts broken away. 40 Fig. 3 is a sectional plan view on line $x-x$, Fig. 1, with parts broken away, and showing the timber-carriage pushed back to carry the timber to the saws; and Fig. 4 is a perspective view of one end of a timber as operated upon 45 by the machine.

The letter A indicates a bed or sill of suitable front and back timbers, $a a'$, respectively connected to longer timbers, $a^2 a^3$, on which Δ or other shaped tracks $b b$ are fixed.

50 B is a bed-frame, which has ways $b' b'$, or it may be wheels, fixed to it and resting on the

tracks $b b$ of the bed A, so that the frame B and the timber-carriage which it supports may be moved to and from and past the saws C D, which are mounted to rotate at right angles 55 to each other in a suitable frame, E, and so as to cut to the same line both ways through the timber.

The frame E is set in a fixed position opposite one end of the timber-carriage, and the 60 saws are driven by belts $c d$, leading to a counter-shaft driven by any convenient motor.

To give the backward and forward traverse to the bed-frame B and the timber-carriage thereon, to carry the ends of the timber to 65 and from the saws, I prefer to employ a rope or chain, F, which is fixed to the opposite bed-timbers, $a a'$, and coils around a drum, F', which is fixed on a shaft, F², journaled in the bed-frame B, and has a hand-wheel, F³, for 70 turning the drum either way, as required. A pinion on the shaft F², meshing with a rack on the bed A, may be used instead of the rope and drum.

On the bed-frame B is fixed the base-frame 75 B', which, as shown, extends beyond the frame B and sill A toward the saws, and on its end next the saws said frame B' supports the timber-carriage, which is constructed with a lower horizontal frame, G, pivoted to the base-frame 80 B' by a strong pintle, H, so as to swing around on the pintle to bring opposite ends of the timber to the saws, as hereinafter more fully explained.

The frame G has Δ -shaped or other suitable tracks, g , on which corresponding plates, i , or wheels fixed to the under side of an upper frame, I, rest, so that the frame I may be slid toward or from the saws to set the ends 85 of the timbers J for the requisite cuts in forming the end tenons, $j j'$, thereon.

To traverse the frame I on the frame G, I prefer to employ a rope or chain, K, fixed to opposite ends of the frame G, and coiling around a drum, K', fast on a shaft, K², journaled in the frame I, said shaft having hand-wheels K³, by which to turn it; and I provide a fixed curved scale-bar, k, on the frame I, said bar having division-marks to indicate by the travel of a pointer fixed to the adjacent 90 hand-wheel, K³, or by a mark on the wheel, the extent of movement of the frame I either

way to set the timbers held in the clamps properly to the saws for length, and to gage the lengths of the end tenons of the timbers. I show a hand-wheel, K^3 , with a scale-bar, k , at both the front and back of the machine; but a front wheel only may be provided.

The frame I may of course be shifted by a rack and pinion or other suitable devices.

The frame I swings around with the frame 10 G on the pintle or king-bolt H as a center, and on the frame I the timber-clamping frame and devices are supported.

The timber-clamp frame L consists of strong posts L', tied together at the top and bottom 15 by stringers L², and having vertical slots L³ through their lower ends, through which slots the heavy bolts M pass into the frame I. The slots L³ allow the clamp-frame to be set higher or lower on the frame I, as the thickness of 20 the timbers shall require, for cutting end tenons of varying sizes on the timbers.

To relieve the bolts M of the weight of the clamp-frame and timber and set the carriage vertically for one of the cuts through the timber, and to avoid excessive use of the screws by which the whole carriage is adjusted vertically, as hereinafter described, I provide interchangeable blocks N, of various thicknesses, which may be set between the lower shoulders, 25 7', of the frame L and the frame I, and these blocks N may be set in place before or after the timber is clamped in the frame or carriage.

The timber-clamps are arranged one at each end of the upper clamp-frame, and consist 30 each of a strong face-plate, O, having a true peripheral edge, so as to be supported by the rollers P, which are journaled in strong boxes Q, fixed, as shown, to the top and bottom tie-bars, L², of the clamp-frame at each end of 35 the frame. I show two rollers, P, at the lower edges of the clamp-plates O, and one roller above; but the number, position, and arrangement of the rollers may vary as desired.

The peripheries of the rollers P are 40 caved to fit the peripheral edges of the clamp-plates, to hold said plates upright, while they are free to revolve edgewise in turning the log or timber to be tenoned. The timber is passed into the central apertures, O', of the opposite 45 clamp-plates O, and is held to the plates by the clamp-screws R, which are threaded through boxes S, fixed to the plates O. The screws have handles R', by turning which one way the points r of the screws will be forced 50 against or into the timber J to hold it to the carriage. I show four screws, R, to each clamp-plate; but more or less than four may be used, 55 as desired.

In setting the timbers J in the clamps of the 60 carriage, and afterward feeding the timber by a vertical movement of the carriage to make successive cuts at each side of the timber to form the end tenons, j j', thereon, the timbers will be placed in the clamp-frame and clamped, 65 and the timber will be adjusted vertically to the saws by the use of blocks N of the proper

thickness until the center of the timber shall be raised above the meeting line of the cuts of the two saws C D, for a distance equaling one-half the width of the smaller end tenons, 70 j, to be formed on the timbers, or, in other words, until the line j', or lower side of the tenon j, shall lie in the plane of the saw D, the frame G of the carriage resting meanwhile on the base-frame B', as in Figs. 1 and 2. I then 75 raise the carriage by means of the strong screws T—which pass through boxes T', fixed to the four corners of the base-frame B', and lift against caps T², fixed to the carriage-frame G—until the edge line j³ of the larger 80 tenon j' of the timber J lies in the plane of the saw D, which brings the timber held in the clamps of the carriage to the proper elevation for taking off the first or outer cuts from each face of the timber at one end. The 85 pointed ends of the screws T are centered in concavities t in the caps T², so that the carriage is held from turning on the pintle H while it is being lifted by the screws T and while the saws are cutting the timber. 90 The timber is placed in the clamps while the carriage is drawn away from the saws to the position in Fig. 1, and when the carriage is elevated to make the first cuts along the end shoulder, j⁴, of the timber and the sides j⁵ of 95 the tenon j' the hand-wheel F³ will be turned to carry the timber to the saws, which will make their first cut. The motion of the wheel F³ will now be reversed to move the carriage back, and the clamp-plates and clamps will 100 be given successive quarter-turns on the rollers P to bring all four faces of one end of the timber to the saws. The screws T then are let down to lower the carriage-frame G to the base-frame B', and the carriage is shifted back 105 a distance equaling the length of the inner tenon, j'. A second cut is taken from each face of the log, which will leave the two end tenons, j j', on the end of the timber, as in Fig. 4. The frame I having been shifted before 110 the sawing commenced, by turning the hand wheel or wheels K³, so as to allow just one-half of the desired length of the timber between the saw C and the center of the pintle H, and one end of the timber having been cut 115 by the saws, as last above described, the screws T will be run clear down out of the sockets t of the caps T², so as to allow the entire carriage-frames G I L and the clamped timber to be swung one-half way round, which 120 will bring the other end of the timber in position to be operated upon by the saws, as the carriage is set vertically by the screws T and traversed by moving the hand-wheel F³, as 125 above described, whereby both ends of the timber will be cut alike, and any number of timbers may be cut exactly to a length, and tenoned at both ends alike, so as to be ready for setting up with mortised heads and sills in mine-shafts, tunnels, and other cuttings, for 130 support of the roof or for other purposes.

In adjusting the frame I along the frame G

for a different length of finished post or timber, the frame I will be moved either way, as required, just one-half of the difference in length between the timbers last cut and those 5 to be cut, the swing of the carriage on the pintle H then leaving the timber the desired length, as will readily be understood.

To provide for working all the screws T at once to maintain the true level of the timber-10 carriage at any elevation, so as to produce square and true work, I have placed upon each of the screws a chain-wheel, V, and I pass around all the chain-wheels the endless chain W, and the chain-wheel at the front right-hand 15 corner-screw T has fixed to it the bevel-gear w, with which meshes the bevel-gear w', held to a short shaft, which carries the hand-wheel X, by turning which all the screws T will be raised or lowered a like distance. I show the chain-20 wheels V fitted to the threads of the screws T, so that the screws work up and down through the wheels; but the chains and chain-wheels may be arranged in any approved way with the screws to cause simultaneous movement 25 of the screws.

A graduated scale-bar, Y, held to the base-frame B' by rods y, indicates by the travel along it of a pointer or mark on the wheel the extent of vertical movement of the carriage.

30 In framing the shorter timbers the carriage will be set out by the cord and pulley K K', so as to be liable to overbalance the carriage and cause it and the frames B B' to tilt downward over the timber a³ of the bed A and toward the saws, and to prevent this I provide a box or trough, Z, along the base-frame B', in which the necessary weights may be placed to hold the carriage upright and level, as will readily be understood.

40 It will be seen that the machine is very compact and all the adjustments can readily be made, as the hand-wheels are grouped or in convenient reach at the front of the machine, so that it may be operated by one man, and 45 round or unsawed or unhewn timbers of any cross-sectional form which may be held in the clamps may have perfectly square and true tenons of uniform size cut on their opposite ends, and the shoulders at the tenons will be 50 perfectly square, so as to set solidly against the cap and sill timbers and make a strong firm structure to support the superincumbent weight.

Having thus described my invention, what I 55 claim as new, and desire to secure by Letters Patent, is—

1. A timber-framing machine constructed with two saws mounted to effect the cutting operation in planes at right angles to and 60 joining each other at a single point, to effect the simultaneous cutting of two sides of a tenon, and with a traversing timber-carriage provided with a rotatable frame having at each 65 side of its opening a timber-clamp, by which the timber may be turned axially to present all of its faces to the saws, and that section of

the carriage carrying the timber-clamps being mounted to rotate horizontally to present both ends of the timber to the saws, substantially as described.

2. A timber-framing machine constructed with two saws mounted at right angles to each other in a fixed saw-frame, and with a traversing timber-carriage provided with a circular rotatable frame mounted upon and between rolls, 75 and provided with timber-clamps, by which the timber may be turned axially, and that section of the carriage carrying the timber-clamps being mounted to rotate horizontally, and also being adjustable to and from the saws, 80 to govern the lengths of the framed timbers, substantially as described.

3. A timber-framing machine constructed with a bed, A, a traversing frame on the bed, and means for moving the frame, a timber-carriage provided with vertically rotatable timber-clamps O R, and said carriage being mounted on a pintle or king-bolt, H, to be rotated horizontally, as specified, in combination with the saws C D, mounted in a fixed 90 frame, E, to rotate at right angles to each other, substantially as shown and described.

4. A timber-framing machine constructed with a bed, A, a traversing frame on the bed, and means for moving the frame, a timber-carriage consisting of a frame, G, a frame, I, fitted to move along the frame G, and means for effecting such movement, and said frame I supporting the rotatable timber-clamps O R, and said carriage being mounted to turn horizontally on a pintle, H, as specified, in combination with the saws C D, mounted in a fixed frame, E, to rotate at right angles with each other, substantially as shown and described.

5. In a timber-framing machine, the timber-clamp frame comprising parallel supplementary frames tied together at top and bottom and disposed upon a traversing frame, in combination with the rings traveling or rotatable upon rolls disposed in the supplementary frames of the timber-clamp frame, together with clamping-screws carried by said rings, substantially as and for the purpose set forth.

6. In a timber-framing machine, the timber-clamp frame comprising parallel supplementary frames tied together at top and bottom and provided with vertical slots, and the rotatable rings having clamping-screws, in combination with the traversing frame provided with holding bolts or screws, together with adjusting-screws acting upon a frame supporting said traversing frame, substantially as and for the purpose set forth.

7. In a timber-framing machine, the timber-clamp frame comprising parallel supplementary frames tied together at top and bottom and provided with vertical slots, and the rotatable rings having clamping-screws, in combination with the traversing frame having holding bolts or screws, together with inter-

changeable blocks inserted between said timber-clamping frame and traversing frame, and the adjusting screws acting upon a frame supporting said traversing frame, substantially as and for the purpose set forth.

8. The combination, with the traversing base-frame, of the timber-carriage having the vertically-adjustable frame mounted upon a central pivot or pintle and carrying a horizontally-rotatable clamp, substantially as and for the purpose set forth.

9. The combination, with the traversing base-frame, of the timber-carriage comprising the frames G L, the traversing frame I, and the clamp-frame O R, said frame having a horizontal rotary movement, and capable of vertical adjustment by means of screws carrying toothed wheels driven by an encompassing chain and beveled gear-wheels, substantially as and for the purpose set forth.

10. The combination, with the traversing base-frame of the timber-carriage, the horizontally-rotatable head portion of the carriage, and the screws T, fitted in boxes on the base-frame, of the caps T², having cavities t, to receive the heads of the screws, to prevent the turning of the carriage until the screws are run clear down from the caps, substantially as shown and described.

11. The traversing frame B', having the ballast-box Z, in combination with the timber-carriage having the traversing frame I, carrying the timber-clamp support, substantially as and for the purpose set forth.
